UNITED STATES PATENT OFFICE.

THOMAS J. KIRKPATRICK, OF SPRINGFIELD, OHIO.

DESIGN FOR A VELOCIPED-E-SADDLE.

SPECIFICATION forming part of Design No. 29,417, dated September 27, 1898.

Application filed February 21, 1896. Serial No. 580,262. Term of patent 14 years.

To all whom it may concern:

Be it known that I, THOMAS J. KIRKPATRICK, a citizen of the United States, residing at Springfield, in the county of Clark and State of Ohio, have invented and produced a new and original Design for Velocipede-Saddles, of which the following is a specification, reference being had to the accompanying drawing, showing a part thereof.

In the drawing I have shown a side elevation partly, in perspective, of a velocipede-saddle, showing my design.

The leading feature of my design consists in a base-bar slightly flattened and substantially straight at the ends and having a drop or curve in the center, where it is slightly enlarged and rounded in cross-section, and having extending therefrom at the ends supports, the main body of each of which is formed substantially circular in outline with the ends projecting in right lines, so as to join the base-bar and also the seat, the ends of which join said supports on the lines described. The circular bodies of the end portions of the frame would, if continued, each form a complete circle, while the laterally-projecting portions, which join the base-bar and seat proper, extend therefrom, so as to lie wholly on the outside of a circle which would con-

tain the said circular body. The seat or saddle cover is slightly raised at the pommel and is curved downwardly at each end toward the supports; besides being slightly drooped at the front and curved, so as to form, with the pommel, a pleasing outline.

In the drawing, *a* represents the base-bar, and *b* and *c* the circular portions of the frame, which join the base-bar at right lines, as shown at *b'* and *c'*, so as to drop below the ends of said bar.

d is the seat which joins the circular bodies *b* and *c* by right lines, as indicated, the seat or saddle cover being curved slightly, as indicated at *d'*, *d²*, and *d³*, so as to form, with the frame and with the circular bodies and base-bar thereof, an attractive and pleasing outline.

Having thus described my invention, I claim—

The design for velocipede-saddle substantially as shown and described.

In testimony whereof I have hereunto set my hand this 15th day of February, A. D. 1896.

THOMAS J. KIRKPATRICK.
